PLUG AND FEATHER CONSTRUCTION

William B. Horton, Concord, Mass., assignor to H. E. Fletcher Co., West Chelmsford, Mass., a corporation of Massachusetts

Application January 30, 1956, Serial No. 562,060

1 Claim. (Cl. 125—36)

This invention relates to a splitting tool of the type commonly referred to in the art as a "plug and feather," being employed particularly in quarries in connection with splitting stone, such as blocks of granite and the like.

This class of splitting tool is useful in granite quarries in splitting slabs of granite which may have already been separated from a quarry bed at considerable expense and which are required to be subdivided with a minimum of waste into desired sizes. The plug and feather tool consists essentially of a wedge-shaped plug and a pair of tapering metal pieces commonly referred to as feathers and adapted to be contained in a drilled hole in the granite slab. The wedge-shaped plug is located between the feathers and serves to drive the feathers apart with great force when struck with a hammer.

If the splitting forces thus produced are exerted through the feathers against those portions of the piece of granite immediately surrounding the top of the drilled hole, there will occur breaking or chipping of stone, a condition referred to as "spalling" and there results an undesirable spoiling of stone. To avoid this, a conventional practice is to counterbore the top of the drilled hole a sufficient depth to prevent spalling. However, this is objectionable in that it adds materially to the cost of processing the granite.

It is an object of the invention to provide an improved splitting tool of the plug and feather type and to devise especially a feather construction which can be used without spalling taking place and which, nevertheless, eliminates the need for counterboring, regardless of the size of the drilled hole into which the plug and feather assembly is inserted. It is a further object of the invention to provide a tool of the class described which is more efficient and convenient to handle and, especially, to position in a drilled piece of granite.

These and other objects and novel features will be apparent from the following detailed discussion of the invention.

To deal with the problems and objectives outlined, I have conceived of the idea of constructing feather components in a plug and feather assembly having as a basic feature stone engaging surfaces so limited in extent that they may be employed in a drilled hole to exert splitting forces in a selective manner and particularly at points sufficiently below the top of a drilled hole to avoid spalling.

I have found that the stone engaging surface of a feather component may be limited in a suitable manner by providing an elongated feather body having a relatively thick bottom portion and a relatively thin upper extension. I construct this elongated body in a special manner such that the relatively thin extension has a dimension measured in a direction at right angles to its longitudinal axes which is small relative to a corresponding dimension of the relatively thick bottom portion so as to interrupt and limit the extent of the area of contact of the stone engaging surface of the thick bottom portion when wedged in a drilled hole.

2

This concept, I find, may be practically and effectively embodied in several different forms and three preferred forms have been illustrated in the accompanying drawings, in which

5 Fig. 1 is a perspective view of the improved feather construction of the invention;

Fig. 2 is a view in cross-section showing a pair of feathers and a plug arranged in an operating position in a drilled hole in a piece of granite;

10 Fig. 3 is another perspective view showing a modified form of feather arrangement, including a pair of feather elements associated together;

Fig. 4 shows a fragmentary detailed plan view of a drilled hole in a granite body having the feather pair shown in Fig. 3 located therein;

15 Fig. 5 is a fragmentary cross-sectional view showing the feather pair of Figs. 3 and 4 combined with a plug member in an operating position;

Fig. 6 is a fragmentary perspective view of still another modification of the invention; and

20 Fig. 7 is a fragmentary cross-sectional view of the structure of Fig. 6.

25 In the structure illustrated in Figs. 1 and 2, I have shown one simple form of feather construction in which an elongated feather body, generally noted by the letter F, is constructed with a relatively thick bottom portion 2 and a relatively thin upper section 4. The feather is preferably constructed along one side with a relatively flat plug engaging surface 6 and along its opposite side with a curved stone engaging surface 8. The extension 4 is preferably constructed with a slightly bent-over shape, as shown, which allows the end of the extension to project outwardly and serve as a handle or tip for holding and positioning the feather in a drilled hole.

30 35 In accordance with the invention, I interrupt and limit the convex stone engaging surface 8 by abruptly relieving the extension 4 to define a relatively sharp shoulder 5 and thus leave a relatively thin portion, as shown in Fig. 1. In Fig. 2, I have further illustrated a pair of feathers

40 combined with a plug 9 to constitute a complete splitting tool with the feather components being engaged in a drill hole 10 of a piece of granite 11. In the position shown, the plug 9 holds the stone engaging surfaces as 8 firmly against the sides of the drilled hole.

45 It will be observed that, in the position described, the feather extensions and plug have a combined dimension measured in a direction at right angles to the longitudinal axes of these members which is small relative to a corresponding dimension measured through the relatively thick stone engaging surfaces. As a result, there will be a clearance as noted at points C and C' between the feather extensions and the hole sides, regardless of the position of the splitting tool, and the effect of this is to localize the area of contact of the stone engaging surfaces of the two feathers at the lower section of the hole.

50 55 Under such conditions, I have found that, if the plug 9 is struck a sharp blow, desirable wedging forces are developed and applied at a distance sufficiently below the surface S of the piece of granite 11 to avoid spalling or otherwise damaging portions of stone immediately surrounding the drilled hole.

60 It is pointed out that, in thus limiting the area of contact of wedging forces to the lower part of a drilled hole by means of the relieved feather feature, not only do I succeed in eliminating spalling but there is also avoided the need for counterboring since the ordinary drilled hole is all that is required to receive the plug and feather arrangement of the invention.

65 70 In Figs. 3, 4, and 5, I have illustrated a form of feather construction in which there is retained the same basic feature of a relatively thick stone engaging feather portion and a relatively narrow or thin extension portion. With

this feature is, however, provided an additional feature of joining together the feathers to make a connected pair and the connecting means may also be utilized to hold the feathers in a properly supported position in a drilled hole.

In forming this connected feather pair of the invention, I employ a connector element, preferably consisting of a steel wire generally indicated by the arrow W. The wire member W is folded upon itself to form a feather retaining loop portion 12 and two right angularly extending legs 13 and 14. These legs 13 and 14 are solidly attached, as by welding or other suitable means, to a pair of special feather sections 15 and 16 along inner surfaces 15a and 16a thereof.

The feather sections 15 and 16 are formed with relatively short tapering stone engaging surfaces which are adapted to perform the same function as surfaces 8, already described in reference to feather F. It will be seen that the parts of the wire W which extend upwardly from the feather sections, as illustrated in Fig. 3, serve to locate the feather sections well below the top of the drilled hole.

In Fig. 4, I have illustrated the connected feather pair arranged in a drilled hole 20 in a mineral body 22, and this figure illustrates more clearly the location of the loop portion 12 resting on the upper surface of the body 22 in a position such that the feather sections 15 and 16 are suspended in spaced-apart relation well down in the hole.

In Fig. 5, I have shown the connected feather pair positioned in an operative position in the hole 20 in the mineral body 22 with a wedge member 24 having been inserted between the feather sections 15 and 16. This figure further illustrates the location of the feather sections well below the surfaces of the mineral body 22 and also shows that the wire member W occurs in spaced relation to the hole to leave clearances 26 and 28 so that no wedging pressure is exerted in the region near the top of the hole.

In this connected feather pair, certain handling and positioning advantages are realized which are not possible with either the conventional type of feather or a feather such as shown in Figs. 1 and 2. The loop portion not only serves to locate the feather sections deep in the hole but also holds the sections in any desired spaced-apart relation to take the plug or wedge member 24 and, when the hammering and splitting operation has been completed, the loop portion 12 serves as a more convenient means of withdrawing both of the feather sections at the same time.

In Figs. 6 and 7 I have illustrated still another modification of plug and feather construction in which somewhat the same basic principle of the invention is employed. Fig. 6 is a fragmentary, perspective view of component parts of the modification arranged for placement in the hole 30 in a fragmentary portion of a mineral

body 31 which is to be split. Fig. 7 is a cross-section taken approximately on the central vertical axis of the hole 30, showing feather components 32 and 33 and a plug 34 in position ready for the splitting operation.

5 This is a form which I have found has certain economics in manufacture and also lasts longer in use. In this form one of the feathers 32 has twice as much taper as a conventional feather, and the second feather is constructed in the form of a shell 33 which has no taper, being merely 10 a strip of metal curved to fit the hole in the stone. The plug 34 has all its taper formed on one side, matching the taper of feather 32; the opposite side of the plug 34 is constructed with a cylindrical surface matching the inside surface of the shell 33.

15 Fig. 7 shows the surface of feather 32 which bears against the stone stopping short of the top of the hole 30, the upper portion 36 of the feather being merely a useful handle for positioning it, thus embodying the principle of the invention. Similarly the outer surface of shell 33 20 stops short of the upper surface of the stone. The shell 33 may or may not have a projecting handle, but I have found it to be unnecessary and so in a preferred form I leave it off, as shown in Figs. 6 and 7.

25 From the foregoing description, it will be apparent that I have provided a desirable and simplified form of plug and feather tool which will avoid spalling and eliminate the need for counterboring. More convenient handling and more accurate placing of the splitting tool can also be carried out.

30 The idea of relieving a feather extension or using a connecting means for joining two feather sections may be embodied in various other forms in addition to those noted in keeping with the spirit of the invention as defined by the appended claim.

35 Having thus described my invention, what I claim is:

A feather member for a stone splitting tool of the plug and feather type for use in a round hole in the stone, said feather member comprising an elongated body having a flat surface adapted to be engaged by a 40 wedge and having an opposite curved bearing surface for engagement with a curved inner surface of the round hole, the elongated body having a recessed portion above the curved bearing surface and extending from below to above the top of the hole and having a portion adapted 45 to extend above the top of the stone and bent outwardly to provide means for manually rotatably adjusting the plug in the hole.
